UNITED STATES PATENT OFFICE.

MARTIN NYHUS, OF ASHLAND, WISCONSIN.

MATTRESS.

1,375,061.

Specification of Letters Patent. Patented Apr. 19, 1921.

Application filed June 4, 1920. Serial No. 386,475.

To all whom it may concern:

Be it known that I, MARTIN NYHUS, a citizen of Norway, residing at Ashland, in the county of Ashland and State of Wisconsin, 5 have invented new and useful Improvements in Mattresses, of which the following is a specification.

This invention relates to mattresses, cushions or the like, including a separable pad, 10 which can be readily and easily removed from the mattress when it is desired to air the same, the invention being particularly advantageous for use in hospitals and similar institutions wherein the mattress can be 15 maintained in a sanitary condition with little or no trouble.

In carrying out my invention, I provide the body portion of the mattress with a raised edge thus defining a depressed center 20 portion, in which the removable pad is adapted to fit, the pad being secured to the raised edge if desired by any suitable detachable fastening means.

Other objects and advantages of the invention will appear when the following detailed description is read in connection with the accompanying drawing, the invention residing in the construction, combination and arrangement of parts as claimed.

30 In the drawings forming part of this application, like numerals of reference indicate similar parts in the several views, and wherein:

Figure 1 is a perspective view of the mattress constructed in accordance with my invention, and showing the pad partly turned over away from the body of the mattress.

Fig. 2 is a fragmentary perspective view showing the pad partly turned back away 40 from the lining with the latter partly broken away.

Fig. 3 is a transverse sectional view taken on line 3—3 of Fig. 1.

Fig. 4 is an enlarged view of several of 45 the springs showing the attaching means associated therewith for the lining or covering.

Fig. 5 is a fragmentary perspective view 50 of the mattress showing the fastening means between the pad and body of the mattress.

Fig. 6 is a detail showing the lining securing means carried by the end of the springs.

Fig. 7 is a similar view of a modified form.

55 Fig. 8 is a similar view of another modified form.

While the invention is described and illustrated as a mattress, I desire to have it understood that the features of the invention may be embodied in pillows, cushions or 60 the like, and all kinds of upholstered furniture.

The mattress herein shown includes a spring frame 10, of the usual construction, including upper and lower frame members 65 between which is arranged a plurality of coiled springs 11. The frame proper may be constructed of steel or rattan or any other suitable material from which the rolled edge may be suitably built up. The spring 70 frame in its entirety is covered by a suitable lining 13. For securing this lining to the respective springs of the frame, I utilize a pair of substantially triangular shaped plates 14 for each spring, these plates being 75 arranged against the opposed ends of each spring and have their corners turned over against one side of the plate, to embrace the adjacent convolutions of the spring. The lining 13 which covers the frame, covers 80 the plate 14, but arranged upon the outside of the lining and upon the adjacent plate 14 is a washer 16 through which the fastening element 17 is passed, this element including bendable prongs 18 which also 85 pass through the washer 19 arranged beneath the convolution of the spring to which the plate is secured. The bendable prongs 18 of the fastening element are bent to lie against the washer 19, and in this manner 90 the lining is effectively secured to the frame. The lining 13 is of course drawn very tight about the frame before being attached to the spring in the manner described. If desired, this lining 13 may also be sewed to the 95 upper and lower members of the frame about the edges thereof. Built up about the spring frame, is a rolled edge 22 which is filled with cotton or other suitable material 23. The raised or rolled edge 22 is 100 of sufficient height to provide the body portion of the mattress with a central depression 24 in which the removable pad 25 is adapted to be fitted. The pad 25 may be loosely arranged within the depression 105 24, or in other words attached thereto as the rolled edges 22 will embrace the edges of the pad 25. However, the pad 25 may be designed to accommodate a flexible element not shown, and through the instrumentality 110 of which the pad 25 may be laced with the rolled edge 24, but as shown in Fig. 5, I

preferably equip the rolled edge 22 with the members 26 forming part of ball and socket connections, the coöperating members 27 being suitably secured to the pad 25.

5 When constructed, the pad 25 can be detachably secured to the body of the mattress, and easily removed therefrom when occasion requires. Manifestly, by reason of the fact that the pad 25 is separable from the body of the mattress, the pad can be removed and easily handled by any one without unduly taxing the strength of the person handling the pad, so that the pad can be aired daily or whenever required. This 10 provides for maintaining the mattress in its entirety in a very sanitary condition, and is a matter of supreme importance in hospitals or the like.

While it is believed that from the foregoing description the nature and advantages of the invention will be readily apparent, I desire to have it understood that I do not limit myself to the details herein shown and

described, and that such changes may be resorted to when desired as fall within the 25 scope of what is claimed.

What I claim is:

1. A mattress comprising a spring frame, a covering for said frame, means for connecting the opposed ends of the spring to 30 said covering, rolled edges built up from said frame, a separable pad reposing upon the frame and lying within the confines of said rolled edges and means for detachably connecting the mattress with said edge. 35

2. A mattress comprising a spring frame, a covering therefor, plates arranged against the opposite ends of each spring and having their turned over portions embracing the adjacent convolutions, washers arranged at 40 opposite sides of said plates and said covering, and fastening elements passed through said washers, covering and plate for securing the springs to the covering.

In testimony whereof I affix my signature. 45
MARTIN NYHUS.
